UNITED STATES PATENT OFFICE.

JOHN F. KENDALL, OF BROOKLYN, NEW YORK.

FUEL-ECONOMIZER.

1,333,116.

Specification of Letters Patent.

Patented Mar. 9, 1920.

Application filed October 10, 1918. Serial No. 257,630.

To all whom it may concern:

Be it known that I, JOHN F. KENDALL, a citizen of the United States of America, residing at Flatbush, county of Kings, Brooklyn, State of New York, have invented certain new and useful Improvements in Fuel-Economizers, of which the following is a specification.

This invention relates to fuel economizers. 10 An object of the invention is to provide a fuel economizer constructed to be applied to or installed in operative relation to a furnace, boiler, steam or other plant utilizing the combustion of fuel, by least modification or alteration of the parts of such fuel combustion apparatus, but thereby attaining an improved efficiency in the utilized heat units derived from the fuel.

20 A further object of the invention is the provision of means for more effectually supplying the required amount of air commensurately with variations of the combustion of the fuel, as the fuel combustion apparatus is varied in operation as desired.

25 In the most preferred form of the invention, as applied to the flue pipe or passage of a heating furnace, the invention comprises a casing adapted to be applied directly to the exterior of the flue pipe, such 30 casing having an inlet for the inflow of air from the atmosphere, and compartments providing a circuitous or angular path of the inflowing air and constructed and arranged to pre-heat the inflowing air and regulate the volume of the pre-heated air in 35 quantity commensurate with the degree of intensity of the combustion of the fuel.

Further objects and features of the invention will be more fully understood from 40 the following detail description and the accompanying drawings, in which—

Figure 1 indicates in vertical-elevation a coal furnace provided with one form of my fuel economizer, the latter being shown in 45 vertical, central section;

Fig. 2 is a cross section of my fuel economizer on line 2—2 of Fig. 1, on a somewhat enlarged scale; and

50 Fig. 3 is a perspective view of my fuel economizer as viewed from above, with the left-hand side wall omitted to more clearly show the construction of the inner parts.

Referring to the drawings, 1 indicates any approved type of coal furnace, having the

flue pipe 2 extending from the outlet box 55 3 of the furnace 1 to the intake 4 of the chimney 5. The fuel economizer 6 is shown combined with the flue pipe 2 on the exterior thereof at a proper location intermediate the outlet box 3 and the intake 4 of 60 the chimney 5. The location, vertically and horizontally, of the fuel economizer relative to the flue pipe of any particular furnace, or other fuel combustion apparatus, is determined from the particular characteristics of 65 such furnace, or other fuel combustion apparatus, as will appear.

The fuel economizer 6 comprises generally the casing 7 having the bottom wall 8 and opposite side walls 9, 10. The air intake 11 is preferably formed in an end wall 12 secured to the bottom 8 and provided with the intake openings 11. The upper portion of the casing 7 is preferably more or less open, for the purpose as appears more 75 fully hereinafter.

The curved flanges 13, 14, respectively secured to the side walls 9, 10 are provided for attaching the casing 7 of the fuel economizer in sealing relation to an exterior face 80 of the flue pipe 2. The end wall 12 may be similarly provided with the attachment curved flange 15^a.

Communication between the interior of the fuel economizer 6 and the interior of 85 the flue pipe 2 is had by means of the air discharge opening 15 which may be either cut in a previously installed flue pipe or provided for in a section of a flue pipe to replace a section or to form a part of the 90 resulting flue pipe.

Intermediate the air discharge opening 15 of the fuel economizer 6 and the air inlet 11, are arranged compartments affording passage of the air and controlling the 95 flow of air commensurately with the effective temperature of combustion, and accordingly commensurate with the extent of evolution of combustible gases in the region of combustion.

100 In the particular embodiment shown in the drawing, I have provided the inwardly tapering compartment 16 communicating at one end with the air intake 11 and at the opposite end with the first or lowest temperature compartment 17 of relatively reduced vertical height and consequent relatively small volume. Such compartment 17

in turn communicates with the second or higher temperature compartment 18 of relatively greater vertical height and greater volume, which compartment 18 in turn 5 communicates with the final or highest temperature compartment 19 of relatively greatest vertical height and greatest volume. Said compartment 19 is open at its top to thereby afford effective heating relation with the flue pipe when the fuel economizer is installed in position. Such arrangement of a set of serially related compartments of relatively increasing volume in the direction of flow of the air therethrough and gradually increasing temperature in heating relation to the flue pipe, is attained in the construction shown by the provision of the partition or wall 21 extending for its major portion substantially parallel to the bottom wall 8, a similar partition or wall 22 disposed in spaced relation to said partition or wall 21 but having the curved portion 23 extending in spaced relation to the end of said partition or wall 21 10 and downwardly to the bottom wall 8, to thereby form the passage 24^a from the compartment 17 to the compartment 18.

The compartment 19 is provided with the regulating discharge openings 24 in the discharge wall 25, preferably positioned at an angle with respect to the plane or region of opening of the discharge opening 15 of the fuel economizer 6, thereby providing for the compartment or pocket 26 located between the discharge openings 24 of the compartment 19 and the discharge opening 15 of the fuel economizer 6. The proper volume of such compartment or pocket 26 is determinable by means of the more or less 15 inclined wall 27 located between the bottom 8 of the fuel economizer 6 and the wall 28 secured to the bottom wall 8. The wall 28 may also be provided with the flange 29 adapted to be secured to the flue pipe 2. Within the compartments 17, 18, I may provide baffles 30, 31, 32, respectively extending 20 transversely to the path of flow of the air therethrough and preferably positioned alternately on the bottom and top walls of the 25 respective individual compartments.

The fuel economizer is applied to such portion of the flue pipe as to effect the location of the discharge opening 15 of the fuel economizer at a point traversed by the back draft indicated by the arrows 34, whereby the preheated air supplied by the fuel economizer is directed into the back draft and thus eventually within the region of combustion of the furnace gases. It will be understood that the discharge opening 15 is of 30 the proper extent of opening for the flow of the preheated air to provide together with the back draft the proper amount of oxygen of increased temperature available 35 within the region of combustion of the fuel

for direct chemical combination with the carbon monoxide and other partially oxygenated carbon and other combustible gases evolved upon combustion of coal or other fuel.

My fuel economizer is also applicable for use with a flue pipe or passage provided with draft regulating means having the construction set forth in my copending application Serial No. 257,628, filed by me the 10th day of October, 1918, entitled Draft regulating means, and operating to reflect and return the back draft through the chimney or stack, and also to separate out and return the partially oxygenated carbonaceous and other combustible gases to the region of combustion. In such use of my fuel economizer, the air supplied to the interior of the flue pipe or passage and thence to the region of combustion, is furnished wholly by the fuel economizer.

In similar manner, my fuel economizer is applicable for use with hot water furnaces, steam and other industrial plants of whatsoever nature utilizing the heat energy evolved upon the combustion of solid or liquid or gaseous fuel.

Whereas I have described my invention by reference to specific forms thereof, it will be understood that many changes and modifications may be made without departing from the spirit of the invention, as defined by the appended claims.

I claim.

1. The combination with a fuel combustion apparatus provided with a flue for the discharge of the products of combustion, said flue being provided with an opening located in a certain portion of the lateral wall thereof, said certain portion extending not greater than one-half of the perimeter of the said lateral wall, of a fuel economizer comprising a casing provided with an open side adapted to communicate with said opening in said lateral wall, said casing being constructed to be applied as a unitary single device to solely said certain portion of said flue, the edges of said open side including edge portions extending but partially about said flue, said casing being provided with an inlet for the admission of air from the atmosphere, partitions disposed within said casing forming in conjunction with the walls of said casing a circuitous passage comprising a portion thereof having its direction of length extending substantially parallel to the passage of said flue and in heating relation with said flue and means for attaching said casing as a single unit to said certain portion of said flue.

2. A casing for a fuel combustion apparatus provided with a flue for the discharge of the products of combustion, said flue being provided with an opening extending through a certain portion of the

lateral wall of the flue, said portion extending not greater than one half of the perimeter of said lateral wall, said casing being provided with an open side adapted to communicate with said opening, said casing comprising bottom, side and end walls rigidly connected to one another, a partition forming in conjunction with said walls of said casing a passage for the flow of air therethrough, a portion of said passage extending in its direction of length substantially parallel to the passage of said flue and in heating relation with said flue, said casing being provided with an inlet for the admission of air into said passage and means for attaching said casing as a single unit to said certain portion of said flue.

3. The combination with a fuel combustion apparatus provided with a circular flue for the discharge of the products of combustion, said flue being provided with an opening extending through a certain portion of the circular wall of said flue, said certain portion extending not greater than one-half of the circumference of said wall, of a fuel economizer comprising a casing having an open side adapted to communicate with said opening, said casing comprising bottom, side and end walls connected rigidly to one another and provided with an inlet for the admission of air from the atmosphere, partitions disposed within said casing and forming in conjunction with said walls of said casing a plurality of passages, means disposed in said passages for retarding the passage of air through said passages and means for attaching said casing as a single unit to said certain portion of said flue.

40 4. The combination with a fuel combustion apparatus provided with a flue for the discharge of the products of combustion, said flue being provided with an opening in a certain portion of its lateral wall, of a fuel economizer comprising a casing having an open side adapted to communicate with the interior of said flue, said casing comprising bottom, side and end walls, said casing being provided with an inlet for the admission of air from the atmosphere, a plurality of spaced partitions disposed interiorly of said casing and forming in conjunction with said walls of said casing an anterior passage of relatively small capacity communicating with said inlet of said casing and a posterior passage of relatively large capacity, said second-named passage communicating with said first-named pas-

sage and means for attaching said fuel economizer to said flue.

5. The combination with a fuel combustion apparatus provided with a flue for the discharge of the products of combustion, said flue being provided with an opening in a lateral wall, of a fuel economizer comprising a casing having an open side adapted to communicate with the interior of said flue, said casing comprising bottom, side and end walls rigidly connected to one another, said casing being provided with an inlet for the admission of air from the atmosphere, partitions disposed interiorly of said casing and forming in conjunction with said walls of said casing a passage of relatively small capacity and a passage of relatively large capacity, said second-named passage communicating serially with said first-named passage and means for attaching said fuel economizer as a single unit to said flue.

6. A fuel economizer adapted to be positioned exteriorly to a certain portion not greater than one-half of the perimeter of a flue constructed for the discharge of products of combustion, comprising a casing having an air inlet and provided with bottom, side and end walls, said casing having an open side, and partitions forming in conjunction with said walls a series of compartments extending in different directions and serially communicating with one another and with said inlet for the passage of air therethrough, said compartments increasing in capacity in the direction of flow of the air through said compartments.

7. A fuel economizer adapted to be positioned to a certain portion of a flue constructed for the discharge of products of combustion, said certain portion being not greater than one-half of the perimeter of said flue, said fuel economizer comprising bottom, side and end walls, said casing being provided with an opening for the flow of air therethrough, a plurality of partitions spaced from one another and forming in conjunction with said walls of said casing a plurality of serially communicating compartments extending in different directions for the passage of air therethrough, said compartments increasing in capacity in the direction of flow of the air, and means disposed in said compartments for retarding the flow of air therethrough.

In testimony whereof I have signed this specification this 5th day of October, 1918.

JOHN F. KENDALL.
